CONTROL OF ELECTRIC LOCKS FOR RAILWAY TRACK SWITCH OPERATING LEVERS

John H. Broadbent, Willistown Township, Chester County, Pa., assignor to The Union Switch and Signal Company, Swissvale, Pa., a corporation of Pennsylvania

Application October 3, 1946, Serial No. 700,862

15 Claims. (Cl. 246—146)

1 My invention relates to traffic protection apparatus, and particularly to apparatus for providing traffic protection for trains moving over hand-operated track switches and to apparatus for providing crossover protection for trains moving along railway tracks which are connected with each other by a crossover track through hand-operated track switches.

A requisite for crossover protection apparatus is that it must be so arranged that a car or locomotive, while occupying a crossover such, for example, as one which interconnects two main tracks, while the switches are in the normal position for train movements along the main tracks, will cause a signal for each main track to indicate stop if the car or locomotive is within fouling distance of that main track. In crossover protection schemes embodying track circuits, one characteristic should therefore be high shunting sensitivity in order to insure that the crossover track circuits will be shunted if the crossover track has high contact resistance due to infrequency of train movements over the crossover.

One feature of my invention is the provision of improved shunting sensitivity through determination of the condition of occupancy of a crossover track by the picking up of a track relay instead of by the release of a track relay.

Another feature of my invention is the provision of normally deenergized track circuits which are arranged to be energized for only brief periods of time. High track circuit voltage can therefore be used without causing excessive waste of energy.

Still another feature of my invention is the provision of manually operable switch operating levers equipped with electric locks, and the provision of a manually operable auxiliary lever also equipped with an electric lock, which upon being operated to its reverse position connects shunts across the main tracks, prepares circuits for unlocking the switch levers in their normal position to permit operation to their reverse position, and prepares a circuit for effecting energization of the track relays.

I shall describe three forms of apparatus embodying my invention, and shall then point out the novel features thereof in claims.

In the accompanying drawings, Fig. 1 is a diagrammatic view showing one form of apparatus embodying my invention, without time locking, in which the switch levers are arranged to be locked in only the normal position and the auxiliary lever is arranged to be locked in only its reverse position; Fig. 2 is a diagrammatic view showing

2 a modification of a portion of the apparatus of Fig. 1 for embodying time locking; and Fig. 3 is a diagrammatic view showing another modified form of the apparatus of Fig. 1, embodying time locking, in which the auxiliary lever is arranged to be locked in both the normal and the reverse positions and to be unlocked in the normal position by remote manual control.

Similar reference characters refer to similar parts in each of the views.

Referring first to Fig. 1, a stretch of railway is shown comprising two main tracks designated by the reference characters **1T** and **2T** connected with each other by a crossover track designated **3T** by the reference character **3T** through hand-operated switches **1W** and **2W**. Each of the tracks **1T** and **2T** is divided by insulated joints **4** to form a section including one of the switches **1W** or **2W**, respectively. Each of these sections is provided with a track circuit including a source of current such, for example, as a battery **5** connected across the rails adjacent one end of the section, and a track relay designated **1TR** or **2TR**, respectively, connected across the rails adjacent the other end of the section.

As shown by the arrows, the normal direction of traffic movements over track **1T** is to the left, which I shall assume is the westbound direction, and the normal direction of traffic movements over track **2T** is in the opposite or eastbound direction. A signal designated by the reference character **1S** is located adjacent the entrance end of the section of track **1T** which includes switch **1W**. A portion of a control circuit for signal **1S** is shown including a contact of relay **1TR**. A signal designated by the reference character **2S** is similarly located adjacent the entrance end of the section of track **2T** which includes switch **2W**. A portion of a control circuit for signal **2S** is shown including a contact of track relay **2TR**.

Track **3T** is divided by insulated joints **4** into two sections **a—b** and **b—c**. Section **a—b** is provided with a track circuit including a source of high track circuit voltage such, for example, as a battery **1Q** connected through a contact of a slow release relay **TP** across the rails adjacent one end of the section, and a track relay **3TR** connected across the rails adjacent the opposite end of the section. Section **b—c** is provided with a similar track circuit including a source of high track circuit voltage such, for example, as a battery **2Q** connected through a contact of relay **TP** across the rails adjacent one end of the section, and a track relay **A3TR** connected across the rails adjacent the opposite end of the section.

Switch 1W is operated by a manually operable lever designated by the reference character 1V having a normal position *n* and a reverse position *r* for moving switch 1W to its normal and reverse positions, respectively. Lever 1V, upon being placed in its *r* position, closes its contacts 12 and 13, and thereby connects a shunt across the rails of tracks 1T and 2T, respectively.

Lever 1V is arranged to be locked in the normal position by an electric switch lever lock comprising a control winding 1NL which controls a dog 6 for engaging some means such, for example, as a notch of a segment 7, which is rigidly connected with lever 1V, when winding 1NL is de-energized. Winding 1NL also controls two armature contacts 22 and 33 which are closed when winding 1NL is deenergized and dog 6 is dropped into the notch of segment 7, and which become opened when winding 1NL becomes energized. A contact 17 of lever 1V, which is included in the control circuit for winding 1NL, is normally closed but becomes opened when lever 1V is moved away from the *n* position. The bow 8 of a padlock 1P, upon being placed in the locking position in the lever latch of the lock for lever 1V, as shown in the drawing, closes a latch contact 34 and opens a second latch contact 16.

Switch 2W is operated by a manually operable lever 2V which is equipped similarly to lever 1V as just described.

Auxiliary lever 3V has a normal position *n* and a reverse position *r*, and upon being moved to its reverse position closes its contacts 12 and 13 for shunting tracks 1T and 2T, respectively. Lever 3V is arranged to be locked in its reverse position by an electric lever lock comprising a control winding 3RL which controls a dog 6 for controlling lever 3V through a segment 9 which is rigidly connected to lever 3V. As indicated by a dotted line in the drawing, dog 6 and armature contacts 14 and 21 of winding 3RL are mechanically interconnected, and are therefore operated together, so that, with dog 6 resting on, and held up by, the outer portion of segment 9, although control winding 3RL is normally deenergized, contacts 14 and 21 of winding 3RL are normally open, but become closed when dog 6 drops into the notch of segment 9 while lever 3V is in its *r* position.

As shown in the drawing, bow 8 of a padlock 3P is removed from the lever latch of the lock for lever 3V. Latch contact 19 of the lock for lever 3V is therefore closed and latch contact 15 is open.

Relay TP is made slow releasing by a multiple connection including a condenser D.

Referring next to Fig. 2, a portion of the apparatus of Fig. 1 is here shown modified for including a time element relay TER for applying time locking to the apparatus of Fig. 1. The apparatus of Fig. 1, modified as shown in Fig. 2, therefore constitutes a second form of apparatus embodying my invention.

Referring now to Fig. 3, another modification of the apparatus of Fig. 1 is here shown for including time locking controlled by a time element relay TER. In this form of apparatus a different type of lever is used for levers 1V, 2V and 3V, so that it is unnecessary to use armature contacts in the electric locks. The normally closed contacts 17 of levers 1V and 3V, shown in Fig. 1, are also omitted in Fig. 3.

Lever 3V is here arranged to be locked in both its normal and its reverse position by engagement of dog 6 with a notch of segment 10 in the normal

and also the reverse position. The energization of electric lock winding 3NRL in its *n* position is controlled by energization of a relay WKR through a manually operable lever 4V which may be located at a remote point such, for example, as a dispatcher's office. In addition to the contacts for shunting tracks 1T and 2T, lever 3V is equipped with a normally closed contact 40 which is included in the circuit for energizing winding 3NRL when lever 3V is in the normal position. Lever 3V also has a reverse contact 43 for controlling relays TER and TP.

Having described, in general, the arrangement of the various parts of apparatus embodying my invention, I shall now describe the circuits and operation in detail.

As shown in the drawings, all parts of the apparatus are in the normal condition, that is, each of the switches 1W and 2W is in the normal position for a train movement along track 1T or 2T, respectively; each of the levers 1V, 2V and 3V is in its *n* position; each of the lock windings is deenergized; bow 8 of each of the padlocks 1P and 2P is in the locking position in the lever latch of the lock for its lever; bow 8 of padlock 3P in Fig. 3 is also in the locking position, but bow 8 of padlock 3P in Figs. 1 and 2 is removed from the lever latch of the lock for lever 3V; track relays 3TR and A3TR and slow release relay TP are deenergized; track relays 1TR and 2TR are energized; and signals 1S and 2S are indicating proceed.

The circuits by which signals 1S and 2S are controlled to indicate proceed include contact 18 of relays 1TR and 2TR, respectively.

I shall assume that, with apparatus arranged as shown in Fig. 1, a traffic movement is to be made over crossover 3T. A trainman will therefore move lever 3V to its *r* position, thereby closing its contacts 12 and 13 and completing a shunt across tracks 1T and 2T, respectively. Relays 1TR and 2TR thus become deenergized, and contacts 18 of these relays open the circuits for signals 1S and 2S, causing these signals to indicate stop. Dog 6 will drop into the notch of segment 9, causing armature contacts 14 and 21 of winding 3RL to close. The trainman will next place bow 8 of padlock 3P in the locking position in the lever latch of the electric lock for lever 3V, thereby opening latch contact 19 and closing latch contact 15.

The trainman will then proceed to one of the switch levers, lever 1V for example, and will remove padlock 1P from the electric lock for lever 1V, thereby opening latch contact 34 and closing latch contact 16 of the lock for lever 1V. Winding 1NL will then be energized by a circuit passing from terminal B of a suitable source of current, not shown in the drawing, through contact 14 of winding 3RL, latch contact 15 of the lock for lever 3V, latch contact 16 of the lock for lever 1V, winding 1NL, and contact 17 of lever 1V to terminal N of the same source of current. The trainman will then move switch 1W to its reverse position by placing lever 1V in its *r* position. Lever 1V, upon being moved away from its *n* position, opens its contact 17 in the circuit for winding 1NL, and closes its contacts 12 and 13 for shunting tracks 1T and 2T, respectively.

The trainman will then remove padlock 2P from the electric lock for lever 2V, thereby opening latch contact 31 and closing latch contact 16 of the lock for lever 2V. Lock winding 2NL will then be energized by a circuit passing from terminal B, through contact 14 of winding 3RL,

latch contacts 15 and 16 for levers 3V and 2V, respectively, winding 2NL, and contact 17 of lever 2V to terminal N. The trainman will then move switch 2W to its reverse position by placing lever switch 2V in its *r* position. Lever 2V, upon being moved 15 away from the *n* position, opens its contact 17 in the circuit for winding 2NL, and closes its contacts 12 and 13 for shunting tracks 1T and 2T, respectively.

I shall further assume that a train then moves 10 over the crossover, but that a car is left on section *a*—*b*, for example, and that a trainman then returns switches 1W and 2W to the normal position by returning levers 1V and 2V to the *n* position. He will then return bows 8 of padlocks 15 1P and 2P to the locking position in the locks for levers 1V and 2V, respectively, and will attempt to return lever 3V to the *n* position. He will therefore remove bow 8 of padlock 3P from the latch of the lock for lever 3V, thereby opening 20 latch contact 15 and closing latch contact 19 of the lock for lever 3V. A circuit will thus be completed for energizing relay TP, this circuit passing from terminal B, through latch contact 19 of the lock for lever 3V, contact 20 of lock winding 2NL, contact 21 of winding 3RL, contact 22 of winding 1NL, back contacts 23 and 24 of relays 3TR and A3TR, respectively, and the winding of relay TP in multiple with condenser D to terminal N. Relay TP, upon becoming energized, closes its contacts 26 and 28.

Relay A3TR will then be energized by a circuit passing from battery 2Q, through a resistor 25, contact 26 of relay TP, rail 3b of section *b*—*c*, winding of relay A3TR, and rail 3a of section *b*—*c* back to battery 2Q. A similar circuit will be closed through contact 28 of relay TP for energizing relay 3TR, but relay 3TR will not pick up against the shunt caused by the car on section *a*—*b*. Contact 29 of relay 3TR will therefore remain open in the control circuit for lock winding 3RL, and hence dog 6 will continue to engage the notch in segment 9, and lever 3V will therefore remain locked in its *r* position.

The trainman will therefore remove padlocks 1P and 2P from the locking position for the electric locks for levers 1V and 2V, respectively. Windings 1NL and 2NL will now become energized by the circuits previously traced and the trainman will then again reverse switches 1W and 2W.

When the car has been removed, so that crossover track 3T is unoccupied, the trainman can return switches 1W and 2W to the normal position. He will then again place padlocks 1P and 2P in the locking position for the electric locks for levers 1V and 2V, respectively. Relay TP will then again become energized by the circuit previously traced. Relay A3TR will then also be energized by its circuit previously traced, and relay 3TR will become energized by its circuit which is similar to the circuit traced for relay A3TR.

Relay TP, on account of being slow releasing due to condenser D, will retain its contacts 26 and 28 closed for a brief period of time after contacts 23 and 24 of relays 3TR and A3TR, respectively, become opened. During this period of time contacts 29 and 30 of relays 3TR and A3TR, respectively, will be closed in a circuit for energizing winding 3RL, this circuit passing from terminal B, through contacts 29 and 30 of relays 3TR and A3TR, respectively, latch contact 31, contact 32 of winding 2NL, contact 33 of winding

1NL, latch contact 34, and winding 3RL to terminal N.

While winding 3RL is energized, the trainman can return lever 3V to its *n* position. Contacts 12 and 13 of lever 3V will thereby be opened and will remove the shunt from tracks 1T and 2T, respectively, permitting relays 1TR and 2TR to again become energized and close their contacts 18 in the circuits for signals 1S and 2S, respectively. If the trainman should fail to return lever 3V to its *n* position before contacts 26 and 28 of relay TP open, relays 3TR and A3TR will become de-energized, and the energization of relay TP, followed by energization of relays 3TR and A3TR will be repeated until lever 3V is returned to its *n* position.

In the form of apparatus shown in Fig. 2, a trainman, in order to reverse switches 1W and 2W, will move lever 3V to its *r* position, as before, and will then place bow 8 of padlock 3P in the locking position in the electric lock for lever 3V, and will remove padlocks 1P and 2P from the electric locks for levers 1V and 2V, respectively. Relay TER will become energized by its circuit passing from terminal B, through latch contact 35 of the electric lock for lever 3V, and the winding of relay TER to terminal N. Upon the lapse of a given period of time, relay TER will close its contact 36, thereby completing a circuit for energizing winding 1NL, this circuit passing from terminal B, through contact 14 of winding 3RL, contact 36 of relay TER, latch contact 16 of the lock for lever 1V, winding 1NL, and contact 17 of lever 1V to terminal N. A similar circuit will also be closed for energizing winding 2NL. The trainman can then move levers 1V and 2V to their *r* position for operating switches 1W and 2W, respectively, to their reverse positions.

When the trainman decides to return the apparatus to the normal condition, he will return levers 1V and 2V to the *n* position, and will remove padlock 3P from the electric lock for lever 3V. A circuit will then be completed for energizing relay TP, this circuit passing from terminal B, through latch contact 19 of the lock for lever 3V, contact 20 of winding 2NL, contact 37 of relay TER, contact 21 of winding 3RL, contact 22 of winding 1NL, contacts 23 and 24 of relays 3TR and A3TR, respectively, and the winding of relay TP in multiple with condenser D to terminal N.

In the form of apparatus shown in Fig. 3, lever 3V is locked in the normal position as well as in the reverse position, so a trainman cannot reverse lever 3V for releasing levers 1V and 2V until permission has been given by operation of lever 4V, at a remote point, to its *r* position, thereby completing a circuit for energizing relay WKR, this circuit passing from terminal B, through contact 38 of lever 4V, and the winding of relay WKR to terminal N. The trainman will remove padlock 3P from the electric lock for lever 3V, thereby closing latch contacts 41 and 46 and opening latch contact 44. With relay WKR energized, a circuit is thus completed for energizing winding 3NRL, this circuit passing from terminal B, through contact 39 of relay WKR, contact 40 of lever 3V, latch contact 41, winding 3NRL, and contact 42 of relay WKR to terminal N. The trainman will then place lever 3V in its *r* position, and will again return bow 8 of padlock 3P to the locking position in the electric lock for lever 3V.

With lever 3V in its *r* position, contacts 12 and 13 will be closed for shunting tracks 1T and 2T,

respectively, thereby causing signals 1S and 2S, respectively, to indicate stop. Also, with lever 3V in its *r* position, its contact 43 will be opened, and its contact 43 will be closed, causing relay TER to become energized by a circuit passing from terminal B, through contact 43 of lever 3V, latch contact 44, and the winding of relay TER to terminal N. Upon the lapse of a predetermined period of time, relay TER will close its contact 45 in a circuit for energizing winding 1NL when the trainman has removed padlock 4P from the electric lock for lever 1V, this circuit passing from terminal B, through contact 45 of relay TER, latch contact 16 of the lock for lever 1V, and winding 1NL to terminal N. Winding 2NL will be energized by a similar circuit. The trainman will then reverse switches 1W and 2W by placing levers 1V and 2V in the *r* position, and will return padlocks 4P and 2P to the locking position in the electric locks for levers 1V and 2V, respectively.

After a train has moved over track 3T, a trainman, in order to return lever 3V to its *n* position, will remove padlock 3P from the electric lock for lever 3V. A circuit will then be completed for energizing relay TP, this circuit passing from terminal B, through contact 43 of lever 3V, latch contact 46, contact 47 of relay TER, contacts 23 and 24 of relays 3TR and A3TR, respectively, and winding of relay TP in multiple with condenser D to terminal N. Relays 3TR and A3TR will then become energized as previously described for Fig. 1, and will complete a circuit for energizing winding 3NRL, this circuit passing from terminal B, through contacts 29 and 30 of relays 3TR and A3TR, respectively, latch contact 31 of the lock for lever 2V, latch contact 34 of the lock for lever 1V, latch contact 41 of the lock for lever 3V, winding 3NRL, and contact 42 of relay WKR to terminal N. The trainman can then return lever 3V to its *n* position, thereby opening its contacts 12 and 13 and permitting signals 1S and 2S to clear. The dispatcher will also return lever 4V to its *n* position.

As shown in the drawings, my invention is applied to crossover protection. By omitting portions of the apparatus shown, my invention can also be applied for traffic protection at single switches.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In traffic protection apparatus for a crossover track which is divided into two sections each of which is provided with a track circuit including a track relay, including a track switch at each end of said crossover track for interconnecting two main tracks, the combination comprising, a manually operable switch lever for each of said switches each having a normal and a reverse position for operating its switch to normal and reverse positions respectively, a manually operable auxiliary lever having a normal and a reverse position, an electric lock for each of said switch levers for locking its lever in the normal position, an electric lock for said auxiliary lever for locking its lever in the reverse position, a normal latch contact for each of said switch levers each closed by application of a padlock in position for locking its lever in the normal position,

means controlled by said normal latch contacts and by front contacts of said track relays for energizing said electric lock for said auxiliary lever, means controlled by said auxiliary lever in its reverse position for energizing said electric locks for said switch levers, traffic governing means which in the operative condition directs traffic movements on one of said main tracks over the associated one of said track switches, and means controlled by said auxiliary lever for placing said traffic governing means in the inoperative condition if said auxiliary lever is moved to its reverse position.

2. In traffic protection apparatus for a crossover track which is divided into two sections and which interconnects two main tracks, the combination comprising, a manually operable switch lever for each of the switches of said crossover track each having a normal and a reverse position for operating its switch to the normal and reverse positions respectively, a manually operable auxiliary lever operable to a normal and a reverse position, an electric lock for each of said switch levers for locking its lever in the normal position, an electric lock for said auxiliary lever for locking its lever in the reverse position, a track relay for each of said sections each connected across the rails of its section, a slow release track repeater relay, means controlled by said auxiliary lever in its reverse position and by a back contact of each of said track relays for energizing said track repeater relay, means controlled by said track repeater upon becoming energized for supplying energy to said track sections for operating said track relays, means including front contacts of said track relays for energizing the electric lock for said auxiliary lever, means including a contact closed if said auxiliary lever is in its reverse position for energizing said electric locks for said switch levers, traffic governing means which in the operative condition directs traffic movements on one of said main tracks over the associated one of said track switches, and means controlled by said auxiliary lever for placing said traffic governing means in the inoperative condition if said auxiliary lever is moved to its reverse position.

3. In traffic protection apparatus for a crossover track which interconnects two main tracks, the combination comprising, a manually operable switch lever for each of the switches of said crossover track each having a normal and a reverse position for operating its switch to the normal and reverse positions respectively, a manually operable auxiliary lever having a normal and a reverse position, means for locking each of said switch levers in the normal position, means for locking said auxiliary lever in the reverse position, means controlled by operation of said auxiliary lever to its reverse position for unlocking said switch levers, track circuit apparatus for said crossover track, means effective upon return of said switch levers to the normal position while said auxiliary lever is in the reverse position for energizing said track circuit apparatus if said crossover track is not occupied, means including said track circuit apparatus in its energized condition for unlocking said auxiliary lever, traffic governing means which in the operative condition directs traffic movements on one of said main tracks over the associated one of said track switches, and means controlled by said auxiliary lever for placing said traffic governing means in the inoperative condition if said auxiliary lever is moved to its reverse position.

4. In traffic protection apparatus for a stretch

of railway track connected with a second track by a switch, the combination comprising, a manually operable switch lever having a normal and a reverse position for operating said switch to a normal position for traffic movements along said second track and to a reverse position respectively for traffic movements over said stretch, a manually operable auxiliary lever having a normal and a reverse position, means for locking said switch lever in the normal position, means for locking said auxiliary lever in the reverse position, means controlled by operation of said auxiliary lever to its reverse position for unlocking said switch lever, train detection apparatus for said stretch of track, means effective upon return of said switch lever to the normal position while said auxiliary lever is in the reverse position for energizing said train detection apparatus if said stretch of track is clear, means including said train detection apparatus in its energized condition for unlocking said auxiliary lever, traffic governing means which in the operative condition directs traffic movements on said second track over said switch, and means controlled by said auxiliary lever for placing said traffic governing means in the inoperative condition if said auxiliary lever is moved to its reverse position.

5. In traffic protection apparatus for a crossover track which interconnects two main tracks, the combination comprising, a manually operable switch lever for each of the two switches through which said crossover track is connected with said main tracks, means controlled by operation of each of said switch levers to a normal and a reverse position for operating its switch to a normal position for a traffic movement along its main track and to a reverse position respectively for a traffic movement over said crossover track, an auxiliary lever manually operable to a normal and a reverse position, means for locking each of said switch levers in the normal position, means for locking said auxiliary lever in the reverse position, means controlled by operation of said auxiliary lever to its reverse position for connecting a shunt across each of said main tracks and for unlocking said switch levers, train detection apparatus for said crossover track, means effective upon return of said switch levers to the normal locked condition while said auxiliary lever is in its reverse locked condition for energizing said train detection apparatus if said crossover track is clear, and means controlled by said train detection apparatus in the energized condition for unlocking said auxiliary lever.

6. In traffic protection apparatus for a crossover track which interconnects two main tracks, the combination comprising, a manually operable switch lever for each of the two switches through which said crossover track is connected with said main tracks, means controlled by operation of each of said switch levers to a normal and a reverse position for operating its switch to a normal position for a traffic movement along its main track and to a reverse position respectively for a traffic movement over said crossover track, an auxiliary lever manually operable to a normal and a reverse position, an electric lock for each of said switch levers each arranged when deenergized to lock its lever in the normal position, an electric lock for said auxiliary lever arranged when deenergized to lock its lever in the reverse position, a first and a second normally open contact of said lock for said auxiliary lever which become closed when said auxiliary lever is locked by its electric lock, means including said

first contact for effecting energization of the electric locks for said switch levers, train detection apparatus for said crossover track, a slow release repeater relay, means including said second contact for energizing said repeater relay if said switch levers are in their normal locked condition and said train detection apparatus is deenergized, means controlled by said repeater relay when energized for energizing said train detection apparatus if said crossover track is clear, means including said train detection apparatus when energized for energizing the electric lock for said auxiliary lever, traffic governing means which in the operative condition directs traffic movements on one of said main tracks over the associated one of said track switches, and means controlled by said auxiliary lever for placing said traffic governing means in the inoperative condition if said auxiliary lever is moved to its reverse position.

20 7. In traffic protection apparatus for a crossover track including a track switch at each end of said crossover track for interconnecting two main tracks, the combination comprising, a manually operable switch lever for each of said switches each having a normal and a reverse position for operating its switch to a normal position for traffic movements along its main track and for operating its switch to a reverse position respectively for traffic movements over said crossover track, a manually operable auxiliary lever having a normal and a reverse position, an electric lock for each of said switch levers each effective if deenergized to lock its lever in the normal position, an electric lock for said auxiliary lever effective is deenergized to lock its lever in the reverse position, a contact of each of said switch lever locks each closed if its lever is locked in the normal position, train detection means for said crossover track, means controlled by said contacts of said switch lever locks and by said train detection apparatus if said crossover track is clear for energizing said lock for said auxiliary lever, means including said auxiliary lever when locked in its reverse position for energizing said switch lever locks, traffic governing means which in the operative condition directs traffic movements on one of said main tracks over the associated one of said track switches, and means controlled by said auxiliary lever for placing said traffic governing means in the inoperative condition if said auxiliary lever is moved to its reverse position.

45 8. In traffic protection apparatus for a crossover track including a track switch at each end of said crossover track for interconnecting two main tracks, the combination comprising, a manually operable switch lever for each of said switches each having a normal and a reverse position for operating its switch to a normal position for traffic movements along its main track and for operating its switch to a reverse position respectively for traffic movements over said crossover track, a manually operable auxiliary lever having a normal and a reverse position, an electric lock for each of said switch levers each effective if deenergized to lock its lever in the normal position, an electric lock for said auxiliary lever effective if deenergized to lock its lever in the reverse position, a latch contact for each of said switch levers each normally open while its lever is in the normal position if a padlock is applied in locking position to its lever latch but which becomes closed when said padlock is removed, means including said latch contact for each of said switch levers upon becoming closed and said auxiliary lever in its reverse position for ener-

11

gizing the electric lock for its switch lever, means controlled by said switch levers in the normal position for energizing the electric lock for said auxiliary lever, traffic governing means which in the operative condition directs traffic movements on one of said main tracks over the associated one of said track switches, and means controlled by said auxiliary lever for placing said traffic governing means in the inoperative condition if said auxiliary lever is moved to its reverse position.

9. In traffic protection apparatus for a cross-over track including a track switch at each end of said crossover track for interconnecting two main tracks, the combination comprising, a manually operable switch lever for each of said switches each having a normal and a reverse position for operating its switch to a normal position for traffic movements along its main track and for operating its switch to a reverse position respectively for traffic movements over said crossover track, a manually operable auxiliary lever having a normal and a reverse position, an electric lock for each of said switch levers each effective if deenergized to lock its lever in the normal position, an electric lock for said auxiliary lever effective if deenergized to lock its lever in the reverse position, a latch contact for said auxiliary lever which is normally open but which becomes closed if a padlock is applied in locking position to its lever latch when said lever is in the reverse position, means including said latch contact upon becoming closed for energizing said switch lever locks, means including said switch levers when locked in the normal position for energizing the electric lock for said auxiliary lever, traffic governing means which in the operative condition directs traffic movements in one of said main tracks over the associated one of said track switches, and means controlled by said auxiliary lever for placing said traffic governing means in the inoperative condition if said auxiliary lever is moved to its reverse position.

10. In traffic protection apparatus for a cross-over track including a track switch at each end of said crossover track for interconnecting two main tracks, the combination comprising, a manually operable switch lever for each of said switches each having a normal and a reverse position for operating its switch to a normal position for traffic movements along its main track and for operating its switch to a reverse position respectively for traffic movements over said crossover track, a manually operable auxiliary lever having a normal and a reverse position, an electric lock for each of said switch levers each effective if deenergized to lock its lever in the normal position, an electric lock for said auxiliary lever effective if deenergized to lock its lever in the reverse position, a latch contact for said auxiliary lever which is normally closed but which becomes open if a padlock is applied in locking position to its lever latch when said lever is in the reverse position, train detection apparatus for said crossover track, a slow release repeater relay, means controlled by said latch contact and by said switch levers in the normal position for energizing said repeater relay if said train detection apparatus is deenergized, means controlled by said repeater relay upon becoming energized for energizing said train detection apparatus if said crossover track is clear, means controlled by said train detection apparatus when energized for energizing the electric lock for said auxiliary lever, means con-

12

trolled by said auxiliary lever in its reverse position for energizing said switch lever locks, traffic governing means which in the operative condition directs traffic movements on one of said main tracks over the associated one of said track switches, and means controlled by said auxiliary lever for placing said traffic governing means in the inoperative condition if said auxiliary lever is moved to its reverse position.

11. In traffic protection apparatus for a cross-over track including a track switch at each end of said crossover track for interconnecting two main tracks, the combination comprising, a manually operable switch lever for each of said switches each having a normal and a reverse position for operating its switch to a normal position for traffic movements along its main track and for operating its switch to a reverse position respectively for traffic movements over said crossover track, a manually operable auxiliary lever having a normal and a reverse position, means for locking said switch levers in the normal position, means for locking said auxiliary lever in the reverse position, a latch contact for said auxiliary lever which is normally open but which becomes closed if a padlock is applied in locking position to its lever latch when said auxiliary lever is in the reverse position, time element means controlled by said latch contact, means controlled by said time element means and by said auxiliary lever in its reverse position for unlocking said switch levers, train detection apparatus for said crossover track, means controlled by said switch levers in the normal position and by said train detection apparatus if said crossover track is clear for unlocking said auxiliary lever, traffic governing means which in the operative condition directs traffic movements on one of said main tracks over the associated one of said track switches, and means controlled by said auxiliary lever for placing said traffic governing means in the inoperative condition if said auxiliary lever is moved to its reverse position.

12. In traffic protection apparatus for a cross-over track including a track switch at each end of said crossover track for interconnecting two main tracks, the combination comprising, a manually operable switch lever for each of said switches each having a normal and a reverse position for operating its switch to a normal position for traffic movements along its main track and for operating its switch to a reverse position respectively for traffic movements over said crossover track, a manually operable auxiliary lever having a normal and a reverse position, means for locking said switch levers in the normal position, means for locking said auxiliary lever in the normal and reverse positions, remote control means for unlocking said auxiliary lever in its normal position, train detection apparatus for said crossover track, means controlled by latch contacts of said switch levers in the normal position and by said train detection apparatus if said crossover track is clear for unlocking said auxiliary lever in its reverse position, time element means controlled by said auxiliary lever in its reverse position, means controlled by said time element means for unlocking said switch levers, traffic governing means which in the operative condition directs traffic movements on one of said main tracks over the associated one of said track switches, and means controlled by said auxiliary lever for placing said traffic governing

means in the inoperative condition if said auxiliary lever is moved to its reverse position.

13. In traffic protection apparatus for a cross-over track including a track switch at each end of said crossover track for interconnecting two main tracks, the combination comprising, a manually operable switch lever for each of said switches each having a normal and a reverse position for operating its switch to a normal position for traffic movements along its main track and for operating its switch to a reverse position respectively for traffic movements over said crossover track, a manually operable auxiliary lever having a normal and a reverse position, an electric lock for each of said switch levers each effective if deenergized to lock its lever in the normal position, an electric lock for said auxiliary lever effective if deenergized to lock its lever in the normal and the reverse positions, remote manually controlled means for energizing said lock for said auxiliary lever in the normal position, a time element relay, means controlled by said auxiliary lever in the reverse position for energizing said time element relay, means controlled by a front contact of said time element relay for energizing said electric locks for said switch levers, a slow release repeater relay, train detection apparatus for said crossover track, means controlled by said auxiliary lever in the reverse position for energizing said time element relay, means controlled by a front contact of said time element relay for energizing said electric locks for said switch levers, a slow release repeater relay, train detection apparatus for said crossover track, means controlled by said auxiliary lever in the reverse position and by a back contact of said time element relay for energizing said repeater relay if said train detection apparatus is deenergized, means controlled by a front contact of said repeater relay for energizing said train detection apparatus, means controlled by said train detection apparatus in its energized condition for energizing the electric lock for said auxiliary lever in the reverse position, traffic governing means which in the operative condition directs traffic movements on one of said main tracks over the associated one of said track switches, and means controlled by said auxiliary lever for placing said traffic governing means in the inoperative condition if said auxiliary lever is moved to its reverse position.

14. In traffic protection apparatus for a stretch of railway track connected with a second track by a switch, the combination comprising, a manually operable switch lever having a normal and a reverse position for operating said switch to a normal position for traffic movements along said second track and to a reverse position respectively for traffic movements over said stretch, a manually operable auxiliary lever having a normal and a reverse position, means for locking said switch lever in the normal position, means for locking said auxiliary lever in the normal and reverse positions, remote manually controllable means for unlocking said auxiliary lever in the normal position, a time element device, a normal latch contact for said auxiliary lever closed only if a padlock is applied in locking position to its

lever latch, a reverse latch contact for said auxiliary lever closed only if the padlock is removed from said lever latch, means controlled by said normal latch contact and by said auxiliary lever in its reverse position for energizing said time element device, means controlled by a front contact of said time element device for unlocking said switch lever, train detection apparatus for said stretch of railway track, means controlled by said reverse latch contact and by said auxiliary lever in its reverse position and also by a back contact of said time element device for effecting energization of said train detection apparatus, means controlled by said train detection apparatus in its energized condition for unlocking said auxiliary lever in its reverse position if said switch lever is locked in its normal position, traffic governing means which in the operative condition directs traffic movements on said second track over said switch, and means controlled by said auxiliary lever for placing said traffic governing means in the inoperative condition if said auxiliary lever is moved to its reverse position.

15. In traffic protection apparatus for a stretch of railway track connected with a second track by a switch, the combination comprising, a manually operable switch lever having a normal and a reverse position for operating said switch to a normal position for traffic movements along said second track and to a reverse position respectively for traffic movements over said stretch, a manually operable auxiliary lever having a normal and a reverse position, means for locking said switch lever in the normal position, means for locking said auxiliary lever in the reverse position, means controlled by operation of said auxiliary lever to its reverse position for unlocking said switch lever, train detection apparatus for said stretch of track, means including said auxiliary lever in the reverse position for effecting energization of said train detection apparatus, means including said train detection apparatus in its energized condition for unlocking said auxiliary lever if said switch lever is locked in the normal position, and means controlled by said auxiliary lever in the reverse position for controlling a signal for said second track to indicate stop.
